GINIA, A CORPORATION OF WEST VIRGINIA.

CAP RETAINER.

Application filed March 18, 1921. Serial No. 453,467.

To all whom it may concern:

Be it known that we, ARCHIBALD W. PAULL and JOHN A. McGINNIS, both citizens of the United States, residing at Wheeling, in the 5 county of Ohio and State of West Virginia, have invented a new and useful Improvement in Cap Retainers, of which the following is a full, clear, and exact description, reference being had to the accompanying 10 drawings, forming part of this specification, in which:—

Figure 1 is a side elevation of a collapsible tube having our invention applied thereto;

Figure 2 is a similar view showing the cap 15 removed; and

Figure 3 is a plan view with the cap removed.

The invention relates to containers having removable caps, and more particularly to 20 collapsible tubes and the like having screw caps which are removed to permit of the discharge of the contents of the tube.

The object of our invention is to provide 25 simple, convenient and inexpensive means whereby the cap when removed remains attached to the tube, so that it cannot become lost, the retaining device acting also to hold the cap sufficiently away from the discharge orifice of the tube to prevent coming in contact with the material being discharged.

In the accompanying drawing, in which we have shown a preferred embodiment of 30 our invention, the numeral 2 designates a portion of a collapsible tube of well known 35 character, having the usual threaded neck portion 3 to receive the cap 4.

5 designates the retaining device and consists of a piece of flexible wire having inherent elasticity. This wire is formed with 40 a loop or eye 6 at one end which is rotatably engaged with the cap below the shoulder 7 thereof, and with a similar loop 8 at the other end which is rotatably engaged with

the neck portion 3 at the base of the screw threads. Intermediate the two eyes or loops 45 the wire is flattened so as to increase its elasticity.

When the cap is applied the intermediate portion of the retainer forms a spring loop as shown in Figure 1. When the cap is unscrewed this loop acts to retain the cap in a position such as shown in Figure 2, where it is held entirely out of the way of the material being discharged from the tube.

By the rotative engagement with both the 55 cap and the tube, the cap may be freely screwed on and unscrewed. It is, however, not necessary that both ends of the retainer shall be rotatively engaged and one end thereof may be made fast either to the cap 60 or to the tube.

Our invention provides an extremely simple retaining device which can be applied to collapsible tubes and the like at comparatively small expense and which has a sufficient spring action to hold the cap away 65 from the mouth of the tube without the necessity of providing spring coils for this purpose.

We claim:

The combination with a container having a neck portion and a cap adapted for detachable engagement with said neck portion, of a retaining device comprising a single piece of resilient metal engaged at one end portion with the cap and at the other end portion with said neck and adapted to automatically lift said cap away from said neck upon disconnection of the detachable connection between said parts, said retaining device having its intermediate portion flat, substantially as described.

In testimony whereof, we have hereunto set our hands.

ARCHIBALD W. PAULL.
JOHN A. McGINNIS.
